INVENTOR

ATTORNEY

UNITED STATES PATENT OFFICE.

LEO LEMM, OF MILWAUKEE, WISCONSIN, ASSIGNOR TO LULA THEIS, OF MILWAUKEE, WISCONSIN.

HOUSING METHOD FOR AIRSHIPS.

Application filed July 27, 1922. Serial No. 577,813.

To all whom it may concern:

Be it known that I, LEO LEMM, a citizen of the United States, residing at Milwaukee, in the county of Milwaukee and State of Wisconsin, have invented new and useful Improvements in Housing Methods for Airships, of which the following is a specification.

This invention relates to a method and means for housing an air ship, the general object of the invention being to hold the ship against lateral and swinging movement while it is being moved into and out of the hangar so as to eliminate danger of the ship being injured or damaged by coming in contact with parts of the hangar through swinging of the ship by high winds or otherwise.

Another object of the invention is to provide a power driven vehicle located on a track for drawing the ship into the hangar and removing it therefrom.

A further object of the invention is to provide means associated with the vehicle for adjusting the height of the ship in relation to the ground.

A further object of the invention is to provide movable shoes for engaging the upper part of the ship to hold the same against swinging movement with tracks for the shoes.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:—

Figure 1 is a view showing the ship about to be placed in the hangar.

Figure 2 is an enlarged view showing the ship attached to the vehicles.

Figure 3 is an end view showing the ship in the hangar.

Figure 4 is a longitudinal sectional view of the telescopic members for raising and lowering the ship.

Figure 5 is a transverse sectional view

showing the means for slidably supporting a shoe.

Figure 6 is a section on line 6—6 of Figure 5.

Figure 7 is a section on line 7—7 of Figure 2.

In these views A indicates the hangar and B the ship. A pair of track members 1 are arranged in the top of the hangar and these members project a considerable distance in front of the hangar. They are arranged at an inclination to each other and to the horizontal, as shown in Figure 3. Each track member is provided with three rail parts, as shown at 2. A pair of shoes 3 is slidably mounted on each track member, each shoe consisting of a frame 4 which has three rollers 5 at each end thereof for engaging the rail parts 2, the shoe proper 3 and the lining or pad 6 for said shoe. These shoes are of slightly curved shape in cross section and are designed to engage the upper part of the body of the ship, as shown in Figures 3 and 5, said shoes engaging the ship an appreciable distance from the top center thereof and adjacent each end thereof so that the ship is prevented from swinging and from moving laterally. The lining or pad 6 will frictionally engage the cover of the body of the ship without injuring the same so that the ship must move longitudinally with the shoes as the same travel along the tracks.

I provide power driven means for moving the ship into and out of the hangar, such means consisting of a pair of motor driven vehicles 7 which are arranged to travel on a track 8 which is preferably embedded in cement 9 so that there is no danger of the ship lifting the track off the ground. The track is provided with rails having T-shaped heads, as shown at 10, so as to provide an upper and lower tread for each rail. Each vehicle is provided with the main wheels 11 for engaging the upper treads of the rail and the auxiliary wheels 12 for engaging the lower treads so that the vehicles are locked to the track and the ship cannot raise the vehicles off the track. The drive means are preferably connected with the wheels 11. The two vehicles are connected together by the long draw bar 13 which has its forked end pivoted to the

vehicles, as shown at 14, and this bar is hollow so that the conductors 15 may pass through the same, these conductors passing from the motor of one vehicle to that of the other and the connections being so arranged that an operator can control both motors from one vehicle.

The means for connecting the ship to the vehicles comprises drums 16, one of which 10 is arranged in each of the end gondolas, a motor 17 for actuating each drum, a cable 18 connected with each drum and the means for adjustably connecting each cable with a vehicle. Such means consists of a mast 19 15 on each vehicle having slots 20 therein, a tubular member 21 fitting over the mast and having pins 22 therein engaging the slots 20 so that the tubular member can slide on the mast but is held against rotary movement thereon, and a rotary member 23 having interior threads engaging a threaded part of the tubular member 21 so that when said member 23 is rotated the member 21 20 will be caused to move longitudinally. The member 23 is rotated by a motor 24 through the gears 25, arranged in a casing 26. The member 23 is mounted on ball bearings 27 and is rotatably connected to the body of the vehicle by the flange 28. The upper end 25 of the member 21 is provided with a pair of gripping jaws 29 for engaging a ring 30 in the end of a cable 18. The jaws are connected by the links 31 with a rod 32 which passes through a hole 33 in the tubular member and has its lower end pivoted to a lever 34 which is pivoted to the member 21 and to which is pivoted a handle 35. These parts are so arranged that normally they 30 occupy a position with the jaws 29 closed but by pushing the handle 35 upwardly the jaws will be opened so as to receive or release the ring 30.

From the foregoing it will be seen that when a ship is to be housed it is brought 45 within a sufficient distance of the ground and in front of the hangar to permit the cables to be connected with the telescopic members by means of the rings 30 and the jaw hooks 29. The motors 17 are then 50 started to cause the drums to rotate so as to wind the cables 18 thereon to bring the ship into a proper position where it can pass under the tracks. If the ship cannot be properly positioned by the drums it can 55 be brought into proper position by moving the tubular members 21 through the motors 24. The ship must be so positioned that it can pass under the shoes without engaging the same. The motors of the vehicles are 60 then started up so that said vehicles can pull the ship under the shoes. The cables are then slackened either by means of the parts on the vehicles or through the drums so as to permit the ship to raise slightly to 65 engage the shoes, as shown in Figure 3. The

vehicles are then started up again to draw the ship into the hangar.

In removing the ship from the hangar the same operation is carried out, the ship being lowered slightly to release it from the 70 shoes after it has left the hangar. The ship is released from the vehicles by pushing upwardly upon the handle 35 to open the jaw members to release the rings 30.

It will thus be seen that the ship is held 75 against lateral and swinging movement as it is being pulled into the hangar or is being removed from the hangar. Thus there is no danger of the ship striking parts of the hangar or being tossed about by high winds. 80

The passengers can enter and leave the ship while it is supported by the shoes so that no difficulty is experienced by passengers in entering and leaving the ship.

The hangar may be provided with the side 85 platforms 36 and the top platform 37 which are so arranged that repairs to the ship can be made while it is in the hangar.

I also provide an extra set of winding means in each gondola so that if anything 90 should happen to the first set the second set could be brought into use, the rings 30' of the second set being engaged by the hooks 39 of the adjusting means. I prefer to place one set of winding means at one end of each 95 gondola and the second set at the other end, as shown in Figures 1 and 2, these figures only showing the rings on the ends of the cables.

It is thought from the foregoing description that the advantages and novel features 100 of my invention will be readily apparent.

I desire it to be understood that I may make changes in the construction and in the combination and arrangement of the several 105 parts, provided that such changes fall within the scope of the appended claims.

What I claim is:—

1. In combination with an air ship and 110 its hangar, a track in the upper part of the hangar and projecting therefrom, sliding members on the track for frictionally engaging the upper part of the ship and power means for moving the ship longitudinally into and out of the hangar.

2. In combination with an air ship and its hangar, a track in the upper part of the hangar and projecting therefrom, sliding members on the track for frictionally engaging the upper part of the ship, power means for moving the ship longitudinally into and out of the hangar, such means consisting of a motor vehicle, means for attaching the same to a ship and a track for the vehicle.

3. In combination with an air ship and 125 its hangar, a track in the upper part of the hangar and projecting therefrom, sliding members on the track for frictionally engaging the upper part of the ship, power means for moving the ship longitudinally 130

into and out of the hangar, such means consisting of a motor vehicle, means for attaching the same to a ship, a track for the vehicle and means for locking the vehicle to its track.

4. In combination with an air ship and its hangar, a pair of track members in the upper part of the hangar and projecting from the same, friction shoes slidably mounted on the track and adapted to engage the upper part of the ship, a motor vehicle, a track for the same extending into the hangar and means for connecting the vehicle with the ship.
- 15 5. In combination with an air ship and its hangar, a pair of track members in the upper part of the hangar and projecting from the same, friction shoes slidably mounted on the track and adapted to engage the upper part 20 of the ship, a motor vehicle, a track for the same extending into the hangar, means for connecting the vehicle with the ship, such

means consisting of vertically adjustable means on the vehicle, a drum carried by the ship, a motor for operating the drum, a cable 25 wound on the drum and means for detachably connecting the cable with the vertically adjustable means on the vehicle.

6. In combination with a ship and its hangar, a pair of track members in the upper part of the hangar and projecting therefrom, a number of cars engaging said tracks, friction shoes carried by the cars for engaging the upper part of the ship, a track on the ground extending into the hangar, a pair 30 35 of motor vehicles engaging the said track, vertically adjustable means on the vehicles for connecting them with the ship, means for connecting the two vehicles together and means for preventing the ship from raising 40 the vehicle off the track.

In testimony whereof I affix my signature.

LEO LEMM.
